[57] CLAIM

The ornamental design for a combined placer mining
suction nozzle and puddling nozzle, as shown and de-
scribed.

DESCRIPTION

FIG. 1 is a side elevational view of a combined placer
mining suction nozzle and puddling nozzle, showing my
new design, the broken lines showing a hose are for
illustrative purposes only and form no part of the
claimed design;

FIG. 2 is a rear elevational view thereof;

FIG. 3 is a front elevational view thereof, shown bro-
ken away for ease of illustration;

FIG. 4 is a side elevational view thereof, the other side
being a mirror image, shown broken away for ease of
illustration;

FIG. 5 is a top plan view thereof; and

FIG. 6 is a bottom plan view thereof.

Fig. 4
